UNITED STATES PATENT OFFICE

2,537,201

SOUND GATHERER

Daniele Amfitheatrof, Pacific Palisades, Calif.

Application November 29, 1948, Serial No. 62,576

3 Claims. (Cl. 181—25)

1

This invention relates to novel and useful improvements in devices for gathering and baffling sound waves, directing the same toward and into the ears of an individual.

An object of this invention is to pivotally support a plurality of baffle sections which are mounted for pivotal and extensible movement with respect to each other, whereby the effective baffling may be selectively regulated.

Other objects and features of novelty, such as simplicity of structure, will become apparent to those skilled in the art, in following the description of the preferred form of the invention, illustrated in the accompanying drawings, wherein:

Figure 1 is a front view of the preferred form of the invention, showing the same in use;

Figure 2 is a perspective view of the device shown in Figure 1; and

Figure 3 is a sectional view taken on the line 3—3 of Figure 2 and in the direction of the arrows.

This invention is adaptable for use primarily by individuals when they desire to listen intently to various sounds, such as in the theater, in "spotting" aircraft, or in any other conditions wherein additional hearing qualities are desired, as in open air concerts and shows.

A resilient band 10 is provided at its ends with annular members 12 and 14, respectively. Each annular member has a pair of brackets 16 and 18, respectively, fixed thereto, accommodating pivot pins.

The pivot pins 20 associated with the brackets 16 have a number of baffle sections 22 mounted for pivotal movement thereon. These baffles are so arranged that they are extensible with respect to each other, rendering the effectiveness of the composite baffles regulatory.

An identical structure is supplied in conjunction with the brackets 18.

It is seen that the preferred material of construction is metal or commercial plastic. Accordingly, a durable device results, which is adapted to be supported on the head of an individual as shown in Figure 1.

2

It will be further noted that the baffle sections are smoothly contoured, being generally arcuate in shape, and one section is adapted to slide over the other in performance of the extensibility feature thereof.

Due to the extreme mechanical simplicity achieved by the invention, a further discussion thereof is deemed unnecessary. However, it is apparent that certain variations may be made 10 without departure from the spirit thereof.

Having described the invention, what is claimed as new is as follows:

1. An apparatus for deflecting sound waves into the ear of an individual comprising a head band having a pair of brackets disposed at each end thereof, and a plurality of superposed baffles pivotally mounted in each of said pair of brackets.

2. An apparatus for deflecting sound waves into the ear of an individual comprising a resilient head band having a pair of brackets disposed at each end thereof, and a plurality of baffles pivotally mounted in each of said pairs of brackets, and said baffles including a plurality of superposed sections mounted for extensible movement 25 with respect to each other.

3. A hearing aid comprising a resilient band adapted to embrace the top portion of the head, a pair of arcuate end members formed on said resilient band, a pair of spaced brackets carried 30 by each of said end members, baffle sections pivotally supported between the brackets of each pair, and said baffle sections being slidably and extensibly disposed on one another for varying the effective length of the composite baffle sections.

DANIELE AMFITHEATROF.
